UNITED STATES PATENT OFFICE.

OSWALD S. PULLIAM, OF PITTSBURG, PENNSYLVANIA.

DRAFT-RIGGING CARRIER AND BODY-BOLSTER.

No. 813,686.

Specification of Letters Patent.

Patented Feb. 27, 1906.

Application filed September 22, 1905. Serial No. 279,682.

To all whom it may concern:

Be it known that I, OSWALD S. PULLIAM, a citizen of the United States, residing at Pittsburgh, in the county of Allegheny and State of Pennsylvania, have invented new and useful Improvements in Draft-Rigging Carriers and Body-Bolsters, of which the following is a specification.

The object of my invention is to provide a new and improved draft-rigging carrier and body-bolster.

In the accompanying drawings, which illustrate an application of my invention, Figure 1 is a top plan view of a draft-rigging carrier and a portion of a body-bolster constructed in accordance with my invention; Fig. 2, a vertical longitudinal section taken on line II-II of Fig. 1; Fig. 3, a cross-section taken on line III-III of Fig. 1; Fig. 4, a perspective view of the central portion of the carrier, and Fig. 5 a perspective view of the central portion of the body-bolster.

Referring to the drawings, the draft-rigging carrier 1, as illustrated and as preferred, is cast in a single piece and is designed to be mounted upon the center sills of a railway-car. The carrier is secured to said sills by bolts passed through ears 2.

Carrier 1 is provided below its top plate 3 with a recess 4, which recess is adapted to receive the recessed portion 5 of the body-bolster 6. Extending outwardly from each edge of the top plate 3 is an angular lug 7. These lugs are adapted to fit into pockets 8, formed on the body-bolster. Carrier 1 is further provided with apertured ears 9, which are arranged to register with and rest upon ears 10, formed on the body-bolster. These ears are secured together by bolts, as clearly shown by Fig. 2. In addition to the ears 10 the body-bolster is provided with ears 11, through which bolts (not shown) are passed to engage with a car-sill.

The body-bolster is formed with the truck-

bolster center-bearing 12, cast integral therewith.

The construction of a combined draft-rigging carrier and body-bolster as above described is particularly designed for use on a car in which the load is mainly carried on the center sill.

What I claim is—

1. The combination, with a cast-metal draft-rigging carrier, of a cast-metal body-bolster secured to the carrier, and a truck-bolster center-bearing cast integral with the body-bolster.

2. The combination, with a cast-metal draft-rigging carrier formed with a recess below its top plate, a cast-metal body-bolster secured in said recess, and a truck-bolster center-bearing formed on the body-bolster.

3. The combination, with a cast-metal draft-rigging carrier formed with a recess below its top plate and provided with lugs projecting from the top plate, a cast-metal body-bolster formed with pockets arranged to receive the lugs of the draft-rigging carrier, said body-bolster secured in the recess of the draft-rigging carrier, and a truck-bolster center-bearing formed integral with the body-bolster.

4. The combination, with a cast-metal draft-rigging carrier formed with a recess below its top plate, lugs projecting from the top plate, apertured ears below the projecting lugs, a cast-metal body-bolster formed with pockets to receive the lugs of the carrier and with ears arranged to register with the ears of the carrier, said body-bolster located in the recess of the carrier.

In testimony whereof I affix my signature in presence of two subscribing witnesses:

OSWALD S. PULLIAM.

Witnesses:

W. G. DOOLITTLE,
MARGARET HUGHES.
